UNITED STATES PATENT OFFICE.

FLOYD J. METZGER, OF NEW YORK, N. Y., ASSIGNOR TO AIR REDUCTION COMPANY, INC., A CORPORATION OF NEW YORK.

FURNACE-TUBE.

1,387,505.

Specification of Letters Patent. Patented Aug. 16, 1921.

Application filed February 6, 1920. Serial No. 356,734.

To all whom it may concern:

Be it known that I, FLOYD J. METZGER, a citizen of the United States, residing at New York, in the county of New York, State of New York, have invented certain new and useful Improvements in Furnace-Tubes; and I do hereby declare the following to be a full, clear, and exact description of the invention, such as will enable others skilled in the art to which it appertains to make and use the same.

This invention relates to furnace tubes employed in the production of alkali metal cyanid by heating mixtures of alkali metal compounds and carbon, with or without catalysts such as iron, in the presence of nitrogen.

The object of the invention is the production of a furnace tube which will successfully withstand the corrosive action of the heating gases and which is not liable to attack by the alkali metal compound, the tube thus becoming, because of its extended life, an effective and economical factor in the commercial fixation of nitrogen.

Further objects and advantages of the invention will be apparent as it is better understood by reference to the following specification and to the accompanying drawing, in which,

Figure 1 is a sectional view of a furnace tube illustrating the disintegrating influence which rapidly destroys the furnace as heretofore used;

Fig. 2 is a longitudinal section through the improved furnace tube;

Fig. 3 is a transverse section through the structure illustrated in Fig. 2;

Fig. 4 is a longitudinal section illustrating a slightly different form of my invention; and

Fig. 5 is a transverse section through the structure illustrated in Fig. 4.

In the practice of the method of producing cyanid by the fixation of nitrogen as described, for example, in Patent No. 1,322,195 granted November 18, 1919, iron and steel tubes were rapidly consumed by oxidation and it was necessary to provide a furnace tube which resisted the oxidizing action of the heating gases. Nichrome tubes were adopted for this purpose and successfully met the problem first encountered. These tubes are, however, cast and frequently con-

tain numerous sand holes and pores which sometimes extend through the wall. Nichrome is not directly affected by the alkali metal carbonate or oxid which forms a part of the furnace charge, but when the carbonate or oxid makes its way through the sand holes or pores to the outer surface of the tube, it combines with the slightly oxidized coating on the tube and forms a blister, which gradually eats its way through the wall and destroys the tube. Nichrome tubes of the size employed are expensive and such tubes under working conditions may have a life extending from a relatively few days to weeks or months depending upon the porosity. The life of the tubes is in any event too short to warrant commercial practice of the method, the cost of replacement of the tubes being too great a factor in the production cost of cyanid.

I have discovered that this difficulty may, however, be readily met and overcome by providing a lining for the tubes which is not affected by the alkali metal compound. Iron or steel is not affected by the alkali metal carbonate or oxid and, since drawn or wrought tubes may be readily procured which have no sand holes or pores, I prefer to use a lining of iron or steel although other material may serve the same purpose. When such a lining is provided, the alkali metal compound cannot reach the outer surface of the nichrome tube and the destructive action referred to is effectually prevented. The iron or steel lining is protected from the oxidizing action of the heating gases by the nichrome and the combination thus provides an ideal furnace tube which has a practically indefinite life and makes the production of cyanid in the manner described entirely practicable and relatively inexpensive.

The iron or steel lining may be fitted closely within the nichrome tube so that substantially no space exists between the walls of the respective tubes. On the other hand, the walls may be slightly spaced and the space may be filled with any suitable filler which should preferably be a good conductor of heat. Finely divided iron which closely packs within the space and thus prevents the entrance of any harmful air current may be used advantageously. It may be desirable to mix with the iron or other filler a proportion of a reducing agent such

as carbon, in quantity sufficient to insure reducing conditions between the tube walls. Practical experience has shown that when the tubes are arranged in spaced relation and the space is filled with finely divided iron as described, heat conduction is not interfered with to any measurable extent and the tube is practically as efficient as when a single tube of nichrome is used.

- 10 Referring to Fig. 1 of the drawing, 5 indicates a nichrome tube in which sand holes or pores 6, which are magnified in the drawing for purpose of illustration, permit passage of the alkali metal compound to the 15 external surface of the tube. The blister 7 is thus formed and, in continued operation, gradually eats its way through the wall of the tube as the alkali metal compound combines with oxid at the bottom of the blister.
- 20 The foregoing represents a condition existing in nichrome tubes employed in carrying out the nitrogen fixation method referred to above.

In Figs. 2 and 3 of the drawing, the improved furnace tube is illustrated as comprising the outer shell 8 of nichrome and the lining 9 of iron or steel closely fitting within the nichrome shell so as to provide substantially no air space between the walls.

30 The combined tubes are mounted in a suitable furnace structure such as is illustrated and described for example, in Patent No. 1,322,195. Such tubes will successfully withstand the destructive action of the furnace gases and of the alkali metal compound indefinitely and consequently replacements of tubes and the consequent expense and loss of time is substantially eliminated.

Figs. 4 and 5 of the drawing illustrate a 40 slightly different form of the invention in which an outer tube 10 of nichrome and a lining 11 of iron or steel are provided. The lining 11 is spaced from the outer tube preferably by a flange 12 at one end and 45 adjusting screws 13 at the other, thus permitting endwise expansion of the tubes independently of each other. Between the tubes a filling 14 of finely divided iron or other suitable material is disposed, the material being closely packed, a result which is 50 accomplished without special attention since the tube is mounted in an inclined position. A reducing agent such as carbon may advantageously be mixed with the iron though 55 it is not essential to the successful accomplishment of the desired result. The space between the outer tube and lining is preferably closed and made air-tight as indicated at 15 by means of asbestos cement or other 60 suitable material.

As above pointed out, heat is conducted through the walls of the duplex tube substantially as through the nichrome tube, formerly used, and consequently the method 65 of making cyanid may be carried out effec-

tively using the novel structure which entirely eliminates the disadvantage referred to of the single nichrome tube.

Various changes may be made in the form, arrangement and construction of the furnace and I desire, therefore, to claim as my invention the arrangement whereby the furnace tube is safeguarded against oxidation and the destructive action of the alkali metal compound. 75

I claim:

1. A furnace tube adapted for use in the fixation of nitrogen by heating mixtures of alkali metal compounds and carbon in the presence of nitrogen, which comprises, an 80 outer shell of oxidation resistant material and a relatively thin inner nonporous shell of material which is not affected by said alkali metal compound.

2. A furnace tube adapted for use in the 85 fixation of nitrogen by heating mixtures of alkali metal compounds and carbon in the presence of nitrogen, which comprises, an outer shell of nichrome and a relatively thin inner shell of ferrous metal. 90

3. A furnace tube adapted for use in the fixation of nitrogen by heating mixtures of alkali metal compounds and carbon in the presence of nitrogen, which comprises, an outer shell of oxidation resistant material, 95 an inner shell of material which is not affected by said alkali metal compound, the walls of said shells being spaced, and a heat conducting filler disposed between said walls. 100

4. A furnace tube adapted for use in the fixation of nitrogen by heating mixtures of alkali metal compounds and carbon in the presence of nitrogen, which comprises, an outer shell of oxidation resistant material, 10 an inner shell of material which is not affected by said alkali metal compound, the walls of said shells being spaced, and a filler comprising finely divided iron disposed between said walls. 11

5. A furnace tube adapted for use in the fixation of nitrogen by heating mixtures of alkali metal compounds and carbon in the presence of nitrogen, which comprises, an outer shell of oxidation resistant material, 11 an inner shell of material which is not affected by said alkali metal compound, the walls of said shells being spaced, and a filler comprising finely divided iron and a reducing agent disposed between said walls. 12

6. A furnace tube adapted for use in the fixation of nitrogen by heating mixtures of alkali metal compounds and carbon in the presence of nitrogen, which comprises, an outer shell of oxidation resistant material, 12 an inner shell of material which is not affected by said alkali metal compound, the walls of said shells being spaced, and a filler comprising finely divided iron and carbon disposed between said walls. 13

7. A furnace tube adapted for use in the fixation of nitrogen by heating mixtures of alkali metal compounds and carbon in the presence of nitrogen, which comprises, an outer shell of nichrome, an inner shell of ferrous metal, the walls of said shells being spaced, and a filler comprising finely divided iron disposed between said walls.

8. A furnace tube adapted for use in the

fixation of nitrogen by heating mixtures of alkali metal compounds and carbon in the presence of nitrogen, which comprises, an outer shell of nichrome, an inner shell of ferrous metal, the walls of said shells being spaced, and a filler comprising finely divided iron and carbon disposed between said walls.

In testimony whereof I affix my signature.

FLOYD J. METZGER.
